Benjamin Klein and Goldie J. Klein,
Long Island City, N. Y.

Application October 29, 1942, Serial No. 108,638

Term of patent 14 years

(Cl. D74—5)

To all whom it may concern:

Be it known that we, Benjamin Klein and Goldie J. Klein, citizens of the United States, residing at 3930 Forty Seventh Street, in the county of Queens and State of New York, have invented a new, original, and ornamental Design for a Combination Calendar and Memo Book, of which the following is a specification, reference being had to the accompanying drawing, forming part thereof.

Fig. 1 is a plan view of a combination calendar and memo book, showing our new design in an open position, the back of the same being plain.

Fig. 2 is an end view of same.

We claim:

The ornamental design for a combination calendar and memo book, as shown.

BENJAMIN KLEIN.
GOLDIE J. KLEIN.
